UNITED STATES PATENT OFFICE.

WILLIE C. BEAM, OF ROCKFORD, ILLINOIS, ASSIGNOR OF ONE-HALF TO THOMAS D. REBER, OF ROCKFORD, ILLINOIS.

SMOKE-PREVENTER.

1,131,107.

Specification of Letters Patent.

Patented Mar. 9, 1915.

Original application filed June 14, 1913, Serial No. 773,709. Divided and this application filed May 25, 1914. Serial No. 840,888.

To all whom it may concern:

Be it known that I, WILLIE C. BEAM, a citizen of the United States, residing at Rockford, in the county of Winnebago and 5 the State of Illinois, have invented certain new and useful Improvements in Smoke-Preventers, of which the following is a specification.

This invention relates to smoke preventers 10 for furnaces where such apparatus is automatically operated to feed a charge of steam and air to the fire, more particularly to the manner of feeding and directing said charge; and this is a division of a patent 15 application filed by me June 14, 1913, Serial Number 773,709, for improvements in regulators.

The object of my invention is to provide 20 in a furnace and smoke preventing apparatus therefor, a novel means for admitting and directing a charge of steam and air to the fire.

In the accompanying drawings: Figure 1 25 is a vertical sectional view through a furnace, passing through the fire door and opening thereof, and illustrating my improvements embodied therewith. Fig. 2 is a view in perspective of the fire-door and door-liner, looking at the back of same.

30 My improvements are adapted to be embodied with furnaces which are provided with time regulated devices for causing a charge of steam and air to be sprayed into the fire-chamber and over the fire when the 35 furnace has been charged with fresh coal, for the purpose of assisting in perfect combustion and for preventing the formation of smoke and soot from the volatile gases that arise from combustion. The injection of 40 steam into the fire-chamber has been done at various points therein, and it is to such matter that my invention relates, together with means for directing the charge of steam in a certain manner and supplying 45 same with a charge of air, thus effecting a different nature and effectiveness of the steam charge.

The furnace shown is of a common structure, comprising a front 3, fire-opening 4, 50 fire-chamber 5, and a boiler 6 having a stack 7 leading therefrom. A fire-door 8 is hinged to the furnace front, covering the fire-opening 4 and is formed with its face offset from the furnace front by sides 9 of the door.

The face of the fire-door is formed with an 55 opening 10 which is covered by a door 11 hinged to the fire-door. The top wall 9 of the fire-door is formed with two apertures 12 spaced apart and opening to the back of the door; and through each of these apertures extends a steam discharge pipe 13 which carries a discharge head 14 adapted to direct steam in a spray toward and over the fire in the fire-chamber. By positioning the steam discharge at this point it is not 60 subject to the intense heat that it would be if located in the fire-chamber, and thus a finer spray jet may be maintained in working order than one located in the latter position where the steam discharge heads are 65 easily rendered ineffective because of the great heat they are subject to; also with this construction no boring through the furnace front is necessary to gain entrance to the fire, and the mounting and structure of 70 the steam feed piping is made very simple, 75 always accessible, and easily repaired.

Steam is supplied to the pipe 13 by a pipe 15, and the passage of steam through pipe 15 is controlled by a time regulator 16, the 80 subject matter of which forms no part of this application so that I have deemed it unnecessary to illustrate its working or operation. The said time regulator is adapted to operate a rock-shaft 17 and open door 11 85 through connection 18; thus the said regulator simultaneously causes a charge of steam to issue from head 14 and to open door 11.

A door-liner 19 is attached to the inner 90 side of the fire-door and has an opening communicating with the fire-door opening 10, the liner opening having deflector walls 95 extending into the fire-opening 4. These deflector walls comprise vertical side walls 20 and a wall 21 which extends from the bottom of the liner opening, upward into the fire-opening at an angle, and terminating below and at fire side of the discharge head 14. Thus the deflector walls form a 100 peculiar guided air passage from the fire-door air inlet to a point adjacent the steam discharge, and such that the air and steam inlets into the fire-opening are from one point and both are diffused into one charge, 105 this concentration giving a force and effectiveness that is not obtained by separately admitting steam and air. The door-liner

wall 21 is provided with vents therethrough; and the door-liner acts also as a means for deflecting heat of the fire from affecting a person standing opposite the fire-door when the air-inlet thereof is open.

5 I claim as my invention:

1. The combination with a furnace having a fire-door opening formed through its front wall, of a steam supply pipe leading to and discharging into said opening at a point adjacent to the outer end thereof, a fire-door covering the outer end of said fire-door opening and having an air opening therein, a movable closure for said air opening, 10 means for operating the said closure and the steam discharge simultaneously, and a deflector on the inner side of said fire-door, said deflector being inclined upwardly and inwardly of said fire-door opening to a point adjacent to and beneath the discharge end of said steam supply pipe, whereby air being guided 15 by said deflector in its passage to the fire is diffused with steam adjacent to the point of discharge thereof, and within said fire-door opening.
- 15 2. The combination with a furnace having a fire-door opening formed through its discharge end of said steam supply pipe, whereby air being so guided in its passage to the fire is diffused with the steam adjacent to the point of discharge thereof and within said fire-door opening.
- 20 3. The combination with a furnace having a fire-door opening formed through its front wall, of a steam supply pipe leading to and discharging into said opening at a point adjacent to the outer end thereof, a fire-door covering the outer end of said fire-door opening and having an air opening therein, a movable closure for said air opening, means for operating the said closure and the steam discharge simultaneously, and a deflector on the inner side of said fire-door, said deflector forming an air guide from 25 said air opening to a point adjacent to the discharge end of said steam supply pipe, whereby air being guided in its passage to the fire is diffused with steam adjacent to the point of discharge thereof, and within said fire-door opening.

Copies of this patent may be obtained for five cents each, by addressing the "Commissioner of Patents, Washington, D. C."

front wall, of an outwardly offset fire door covering the outer end of said fire-door opening, and having an air opening therein, a steam supply pipe extending through the top of said fire-door and discharging into the outer end of said fire-door opening, a movable closure for said air opening, means for operating said closure and the steam discharge simultaneously, and a deflector on the inner side of said fire-door, said deflector being inclined upwardly and inwardly of said fire-door opening to a point adjacent to and beneath the discharge end of said steam supply pipe, whereby air being guided by said deflector in its passage to the fire is diffused with steam adjacent to the point of discharge thereof, and within said fire-door opening.

In testimony whereof I have hereunto set my hand in presence of two subscribing witnesses.

WILLIE C. BEAM.
